UNITED STATES PATENT OFFICE.

WILLIAM A. UTTZ, OF FORT WORTH, TEXAS.

SAFETY ATTACHMENT FOR LOCOMOTIVE-CABS.

1,130,354.

Specification of Letters Patent.

Patented Mar. 2, 1915.

Application filed August 25, 1914. Serial No. 853,447.

To all whom it may concern:

Be it known that I, WILLIAM A. UTTZ, a citizen of the United States, residing at Fort Worth, in the county of Tarrant and State of Texas, have invented certain new and useful Improvements in Safety Attachments for Locomotive-Cabs, of which the following is a specification.

My invention relates to safety devices for escaping from locomotive engine cabs, and more particularly to a detachable carrier to be discharged from the engineer's cab in case of danger; and the object is to provide a carrier or protecting device into which the engineer can inclose himself instantly in time of danger and which device will be automatically detached from the cab and delivered to the ground or other place for the protection of the engineer.

The object is to provide a device which will inclose the engineer and protect him against falling on the ground or stones or other dangerous objects and which can be sealed air and water tight and provided with a valve which the engineer can operate.

The object is to protect the engineer against fire and water or hot steam and to provide a ready means of escape from the engine.

One object is to provide a carrier or deliverer which cannot be crushed or will not be crushed in times of accident and danger.

Other objects and advantages will be fully explained in the following description and the invention will be more particularly pointed out in the drawings.

Reference is had to the accompanying drawings which form a part of this application.

Figure 1 is a front elevation of the device, as arranged in an engineer's cab, providing a seat for the engineer. Fig. 2 is a vertical section of the same. Fig. 3 is a plan view of the same. Fig. 4 is a plan view with the seat removed. Fig. 5 is a detail view of the mechanism for causing the lid to fall instantly when the lid is released. Fig. 6 is an enlarged detail view of the hinge for connecting the lid to the carrier. Fig. 7 is another view of the same, being at right angles to the view in Fig. 6. Fig. 8 is a plan view of the lid, showing a variation in the manner of hinging the lid to the deliverer. Fig. 9 is a vertical section of the shell or casing without the upholstering, showing the man-

ner of bracing the shell with angle or channel iron. Fig. 10 is a side elevation of the carrier or deliverer closed. Fig. 11 is a detail view of the lid and the means for bracing the lid. Fig. 12 is a bottom plan view of the lid. Figs. 13 to 20 inclusive illustrate a carrier which is a slight variation from the carrier previously shown. Fig. 13 shows a front elevation of a carrier closed. Fig. 14 is a vertical section, taken on the side. Fig. 15 is a horizontal section. Fig. 16 is a plan view. Fig. 17 is a side elevation closed. Fig. 18 is a vertical section from the front. Fig. 19 is a top plan view. Fig. 20 is a horizontal section, showing a variation in the shell.

Similar characters of reference are used to indicate the same parts throughout the several views.

The improved safety device has a sheet metal shell 1 which may be braced on the interior by channel iron 2. The bottom of the shell or casing 1 is made heavy by solid metal 3 so that the device will stand on the bottom and even resume an erect position if it should be turned down on the side. The casing is upholstered on the interior by a lining 4 and springs 5 and braced by the channel iron 2. In order to prevent rapid passage of heat and cold through the casing, a lining of asbestos 6 may be placed next to the shell 1. The carrier, shown in Figs. 1-12 is to be mounted in the engineer's cab with the body flush with the floor and suspended below the floor of the cab. A seat 7 is provided for the engineer and provision made for the descent of the seat into the carrier. Vertical bars 8 of T-iron are attached to the channel iron 2 and project close to the top of the body of the carrier and bars of T-iron 9 are pivotally connected to the bars 8 in the manner shown in Figs. 6 and 7. The seat 7 is attached to the slides 10 by brackets 11 and braces 12. The slides 10 consist of channel iron with the edges bent to engage the T part of the T-irons 8 loosely so that the seat can slide upwardly and downwardly on the T-irons 8 and 9 freely.

The slides 10 will break the joints in the T-irons 8 and 9 and the seat will be held in the normal position above the floor of the cab by pins 13 which are inserted in the flanges of the T-irons 8, the slides 10 resting on the pins 13. The seat is thus held in place by the T-irons 8 and 9 and the slides 10 rest-

ing on the pins 13. The seat 7 may be made to descend into the body or casing by pulling on a lever 14 which is fulcrumed on one of the slides 10. A link bar 15 is pivotally connected to the lever 14 and pivotally connected to a bell crank lever 16 which is fulcrumed on the slide 10 with the lever 14. The lever 16 is pivotally connected to the jointed pin 13. Both slides 10 may be provided with levers 16 and pins 13 if necessary. A pull on the lever 14 will let the seat 7 drop to the position of the dotted outline in Fig. 2.

The carrier is provided with a lid 17 which is attached to the T-irons 9. See Fig. 15. 2. Bars 18 connect the T-irons 9 with the shell of the lid and the lid 17 can be attached to the T-irons 9 in any other suitable manner. The lid cannot be closed until the seat descends into the carrier 1, but as soon 20 as the slides 10 pass down off the T-irons 9, the lid is free to fall. In order to make a positive throw for the lid, a lug 19 is attached to the lid and a spring 20 is attached to a bracket 21 which is to be attached to a 25 convenient part of the cab. The spring 20 stands compressed against the lug 19 and as soon as the seat releases the lid, it will fall, being started by the spring 20. The safety device is mounted in the cab by hinged bands 30 or hoops 22 which are attached to the engine frame in any suitable manner. The bands are brought together and held in operative position by pins 23, the bands having interlocking joints to receive the pins 23.

35 Wire cables or cords 24 and 25 are connected to the pins 23 and connected to the lid 17 so that when the lid falls, the pins 23 will be drawn from the joints of the bands 22 and thus release the bands 22 from the carrier.

40 Additional mounting devices for the carrier consist of hanger rods 26 which are attached to the timbers of the cab and hang down by the casing or shell 1. The lower ends of the hangers 26 have holes to receive 45 supporting pins 27 which are held normally projected through the shell 1 into the hangers 26 by springs 28. The pins 27 are provided with guides 29 and are automatically withdrawn from the hangers 26 when the lid falls. The pins 27 are attached to a flexible cord 30 and a cavity 31 is formed in the weighted portion 3 of the carrier. A buffer 32 is attached to the bottom of the seat 7. When the seat falls the buffer 32 will strike

50 the cord 30 and force the same downwardly (see Fig. 2) to the position of the dotted outline. This action will draw the pins 27 out of the hangers 26 and thus release the carrier from the hangers. The hoops or bands 55 22 are connected by interlocking joints in front as well as on the back. The interlocking joint is released at the same time the interlocking joint in the rear is released by the cables 24 and 25. The interlocking joint in

60 65 front is held locked by a pin 33. A bar 34 is

mounted in guides 35 to move freely through these guides. The bar 34 carries lugs 36 adapted to strike the pins 33. When the lid falls it will strike the bar 34 and the lugs 36 will knock the pins 33 out of the interlocking joints and thus release the bands or hoops 22. The pins 23 will be released slightly before the pins 33, but the pins 33 and the pins 27 will be released simultaneously so that the carrier will fall out of the engine cab. The seat 7 is mounted on the slides 10 and is provided with cushion springs 37 which are supported on vertical bars 38 which rest on the platform 39. A shield 40 is made rigid with the platform to 70 protect the elements behind the shield. In addition to the braces for the seat heretofore noted, the seat is braced by the bars 18 which are connected to the lid and to the T-irons 9. Means are provided for locking the lid in a 75 closed position. A catch 42 is rigid with the interior of the casing and a spring catch or lock 43 is attached to the lid. When the lid falls the lock 43 will catch in the catch 42. The lock 43 is in the form of a bell 80 crank lever and a spring 44 normally holds the lock in the locking position, but the person inside can open the lid by pressing on the back end of the lever. A person on the outside can open the lid by taking out the 85 screw 45 which mounts the spring and thus displace the spring so that the device can be unlocked.

When the carrier starts out of the engineer's cab, swinging rods 46 are used to 100 shift the lower part of the carrier out toward the side so that the carrier will not fall directly in the railway track. The rods 46 are pivotally connected to some part of the cab and are provided with yokes 47 which 105 engage lugs 48 on the side of the carrier.

The safety device herein described has been set forth for the use of the engineer. It is apparent that the device is also adapted for the use of the fireman and other 110 workmen on moving trains or other devices.

The lid 7 is provided with a valve 49 hingedly connected to the lid and normally closing an opening which can be used to obtain fresh air. The valve may be operated by a rope or cord 50.

Instead of hinging the lid 7 to the T-irons, as heretofore set forth, the lid may be hinged to the shell 1, as shown in Figs. 8-12.

The variations shown in Figs. 13-20 comprise a safety device for the same purpose as the device previously described and similar in design. The construction varies from the construction previously described. There is merely a change in the body of the device. The shell is composed of two parts 51 and 52. The part 51 is the main body and the part 52 is movable relative to the part 51 and is adapted to telescope into a 125 130

casing formed within the part 51. The casing or space 53 is shown in Figs. 14, 15, 18, and 20. The part 52 is provided with a handle 54 for the convenience of the engineer or other party who wishes to close the carrier or deliverer. Each part 51 and 52 is approximately 180 degrees and the part 52 is provided with a handle 54 by which the engineer can close the device by pulling the movable shell around out of the space 53. The movable section 52 is guided by the outer or stationary part 51 and by a stationary half shell section 55. In this form of safety device, the entire casing, consisting of parts 51 and 52 mounted with the floor flush with the floor of the cab, as shown in Figs. 13, 14, and 18. Locking pins 56 may be used for mounting the casing. The opening through the cab floor is lined with a flanged ring 57 and the pins 56 made to engage the ring 57. The pins 56 have upstanding lugs 58 which project up through a disk 59 which has cam slots 60 therein for the lugs 58. The disk 59 has a laterally projecting shank 61 which is perforated to receive the end of an actuating lever 62 which is fulcrumed in a bearing 63. When the disk is turned by the lever 62, the pins 56 will be drawn out of their sockets so that the casing will fall out of the cab. In order that a person may not be thrown from one end of the casing to the other a buffer or partition 64 may be mounted in the casing and drawn down within the casing by a cord 66 until the buffer rests on supports 69 to which it may be locked by the dogs 68. The buffer may be provided with upholstering 65. A spiral spring 67 may be used to bring the disk 59 to normal position. When the casing starts out of the cab, a chute 70 will guide the device as it is descending and a spring 71 will bear against the opposite side to aid in giving the device the proper direction when falling. A shield 72 is attached to the step of the cab to prevent the safety device from striking the step and being thrown under the car or cab.

In the form of safety device shown in Figs. 1 to 12 inclusive, the casing 1 is hung with the top part of the casing flush with the cab floor and the seat 7 is mounted on a platform 39 which is flush with the floor of the cab. When the seat is thrown down, the platform 39 descends with the seat. The lid 7 has upholstering 73 which serves as a back for the seat and which will prevent the engineer from being struck by the T-irons 9 while the seat is descending. The lower T-irons 8 may be attached to the shell 1 by brackets 74 riveted to the T-irons and to the shell.

In the form of safety device shown in Fig. 20, the moving part of the device may be made in two parts 75 and 76.

In order to make a positive throw of the lid 7, a cord 77 may be attached to the lid and to the seat 7, enough slack being provided to let the seat far enough out of the way of the lid.

What I claim, is,—

1. A safety attachment for the cabs of locomotives comprising a casing attached to the cab and provided with a lid, a seat provided with means for holding the lid in open position, and means by which a person can, after entering the casing, close the lid. 70

2. A safety attachment for the cabs of locomotives comprising a casing detachably attached to the cab for containing a person, a seat adapted to drop into said casing, a lid for closing the casing, and means by which a person can cause the seat to descend into the casing and simultaneously close the lid and detach the casing from the cab. 80

3. A safety attachment for the cabs of locomotives comprising a casing detachably attached to the cab and provided with a lid hingedly connected therewith, a seat and means supporting the seat at the entrance to the casing, means for detaching the seat from its support, and means to be actuated by the falling seat for automatically detaching said casing and simultaneously closing said lid. 90

4. A safety attachment for the cabs of locomotives comprising a casing detachably mounted in the cab standing normally open, a seat supported above the casing and adapted to descend into the casing, means for closing the casing, and means by which a person can, after entering the casing, close the casing and detach the casing from the cab. 100

5. A safety attachment for the cabs of locomotives comprising a casing detachably mounted in the cab, a seat, means for supporting the seat at the entrance to said casing consisting of T-irons having stationary portions connected to the interior of the casing and hinged portions connected to the stationary portions, channel bars attached to the seat and engaging said T-irons and breaking the joints thereof while supporting the seat, pins supporting said channel bars on said T-irons, and a lever operatively connected with said pins. 105

6. A safety attachment for the cabs of locomotives comprising a casing detachably mounted in the cab, a seat supported at the entrance to the casing, means whereby a person sitting on the seat can release the same so that the person can descend into the casing, and means actuated by the falling of the seat for releasing said casing from the cab. 120

7. A safety attachment for the cabs of locomotives comprising a casing, hanging devices for mounting said casing in the cab, a lid for closing said casing, a seat at the 130

entrance to said casing operatively connected with said lid, means for releasing said lid for closing the same, and means carried by said seat for releasing said lid from the open position and for releasing said hanging devices.

8. A safety attachment for the cabs of locomotives comprising a casing, bands and hangers for mounting said casing in the cab and locking pins holding said casing and bands and hangers together, a seat mounted at the entrance into said casing and provided with means for actuating the pins in said hangers when the seat falls, a lid hingedly connected to said casing and means connected with said seat for holding the lid in open position, means connected to said lid for releasing the pins from said bands to be actuated when the lid falls, and means for releasing the seat for allowing the seat to descend into said casing.

9. A safety attachment for the cabs of locomotives comprising a casing detachably mounted in the cab and provided with a lid held in open position, a seat supported against said lid and said lid forming a back for the seat, means by which a person can, after entering the casing, close the lid and simultaneously detach the casing from the cab, and means guiding the casing out of the cab.

10. A safety attachment for the cabs of locomotives comprising a casing detachably mounted in the cab and provided with a lid hingedly connected with the casing, means by which a person can, after entering the casing, close the lid and simultaneously detach the casing from the cab, a valve in said lid, and means for operating the valve.

40 11. A safety attachment for the cabs of locomotives comprising a casing and means attaching the same to the cab, a seat, guiding members for directing said seat down in said casing, and means detachably mounting said

45 seat on said guiding members.

12. A safety attachment for the cabs of locomotives comprising a casing and means

for attaching the same to the cab, a lid hingedly connected to said casing, a seat, guiding members for directing said seat down within said casing, and means detachably mounting said seat on said guiding members, said lid forming a back for the seat and said seat serving to hold the lid open.

55 13. A safety attachment for the cabs of locomotives comprising a casing and means attaching the same to the cab, a seat, guiding members rigid within said casing for said seat and having hinged members projected above said casing, a lid hingedly connected to said casing and forming a back for said seat, sliding members rigid with said seat and engaging said guiding members and breaking the joints in said guiding members 60 when supporting said seat in the normal position above said casing, and means detachably connecting said sliding members to said guiding members.

65 14. A safety attachment for the cabs of locomotives comprising a casing and means attaching the same to the cab, a seat, guiding members rigid within said casing for said seat and having hinged members projected above said casing, a lid hingedly connected 70 to said casing and forming a back for said seat, sliding members rigid with said seat and engaging said guiding members and breaking the joints in said guiding members when supporting said seat in the normal 75 position and above said casing, means detachably mounting said sliding members on said guiding members, and operatively connecting said seat to said lid whereby said lid is closed when the seat descends into said 80 casing.

85 In testimony whereof, I set my hand in the presence of two witnesses, this 22nd day of August, 1914.
